UNITED STATES PATENT OFFICE.

LOUIS GATHMANN, OF CHICAGO, ILLINOIS.

VERTICAL CENTRIFUGAL BOLT OR SEPARATOR.

SPECIFICATION forming part of Letters Patent No. 319,574, dated June 9, 1885.

Application filed February 27, 1884. (No model.)

To all whom it may concern:

Be it known that I, LOUIS GATHMANN, of Chicago, in the county of Cook and State of Illinois, have invented certain new and useful 5 Improvements in Vertical Centrifugal Bolts or Separators; and I do hereby declare that the following is a full, clear, and exact description thereof, reference being had to the accompanying drawings, and to the letters of reference 10 marked thereon, which form a part of this specification.

This invention relates to that class of centrifugal separators in which the axis of the rotating beater-drum is vertical, and in which 15 the material is fed in at the bottom, and the refuse or unbolted portions of the material are discharged at the top, the material being lifted or carried from the bottom to the top of the machine by the mutual operation of inclined 20 beaters or spiral flanges upon the central rotating drum and the surrounding stationary parts.

One object of the invention is to provide in 25 separators of the class mentioned an improved means for regulating the rapidity of the upward movement of material through the machine.

In machines of the character above described the degree of elevating force by which 30 the material is carried upward is dependent upon the inclination of the beaters or spiral drum-flange; to the speed at which the drum is rotated, and to the proximity of the surrounding stationary parts, the revolving parts 35 of the drum operating both by impact upon the material and by the production of a rotary and upward air-current in the space between the drum and the exterior screen. With reference to the said air-current, it follows that 40 if the rotary movement of the air within the space between the drum and the screen is checked to a greater or less extent by narrowing the space between the drum and the surrounding screen at one or more sides of the 45 drum, the upward movement of the air will be correspondingly accelerated, and the material will be carried more rapidly upward through the machine. In view of these facts, and as an improved means for regulating the 50 upward passage of material through machines of the character described, I place one or more

vertical partitions or valves in the space surrounding the drum, the said partitions being inwardly and outwardly adjustable, so as to vary the space for the lateral passage of air, 55 and to thereby control its upward movement and the upward movement of the material through the machine.

Another object of this invention is to provide means in a vertical centrifugal separator for obtaining a more uniform bolting action throughout the entire vertical length of the bolt, and to secure a compensation for the less force with which the material is borne against the bolting-cloth at the upper than at the lower parts 65 of the machine. To this end the bolting-cloth is made in sections of unequal fineness, the coarser being placed above the finer.

The invention consists in the improved features of construction above stated, and also 70 in other matters hereinafter described, and pointed out in the claims.

In the accompanying drawings, Figure 1 is a side elevation of my improved vertical centrifugal bolt, having portions of the exterior 75 casing broken away, so as to show the interior drum, provided with a spiral rib or flange, and also the sectional bolting cloth or screen surrounding the drum, together with other features of construction in the machine. Fig. 80 2 is a horizontal section of the machine taken upon line $x-x$ of Fig. 1. Fig. 3 is a central vertical section of the machine, taken upon the line $x-x$ of Fig. 2. Fig. 4 is a central vertical section taken upon line $y-y$ of Fig. 2. 85 Fig. 5 is an enlarged fragmentary view of the exterior of the beater-drum. Fig. 6 is a face view of one of the adjustable portions illustrated in Fig. 2. Fig. 7 is a side view of the partition or valve strip shown in Fig. 6. Fig. 90 8 is a side elevation of the partition or valve strip shown in Fig. 6, illustrating a modified form of the transverse ribs thereon. Fig. 9 is an enlarged view of a part of one of the spiral flanges on the drum. Fig. 10 is a view of the 95 sheet-metal strip or blank from which the said flange may be formed. Fig. 11 is a vertical axial section of the drum, illustrating a modified construction in the spiral flanges thereof. Fig. 12 is a detail exterior view of a part of the 100 drum shown in Fig. 11. Fig. 13 is a detail view illustrating an undulating form of the

spiral flange upon the drum. Fig. 14 is a fragmentary sectional plan view illustrating the construction of the undulating spiral flange shown in Fig. 13.

5 The principal part of the frame of the machine, in the form thereof which is herein illustrated, consists of two parallel beams, A A, forming the base of the machine, and two parallel uprights, A', arranged upon opposite sides of the machine, said uprights being connected near the base of the machine by cross-beams a a' and at the top by cross-beams A². The two uprights A' are considerably greater in width than thickness, and are located with 15 their plane sides parallel to each other, forming two opposite sides of the outer casing or housing of the machine. The said uprights A' are, as herein shown, cut away in their middle portions, so as to form opposite elongated vertical slots A³, extending from a point near the bottom to a point near the top of the said uprights.

Upon the inner faces of the uprights A', adjacent to and at either side of the slots or apertures A³, are secured vertical posts A⁴, which serve as points of attachment for the lateral margins of the laterally opposite parts or sections of the screen or bolting-cloth B. Said screen is, as herein shown, made in two separate sections, forming parts of cylinders, said sections consisting of suitable skeleton frames having vertical bars b and circumferential ribs b' secured by screws or other suitable means to the posts A⁴.

35 Within the screen or bolt B, and concentric therewith, is located a drum, C, which, as herein shown, is secured upon an axial shaft, C', which rests at the lower end in a suitable step, c, on the cross-beam a', and rises at its 40 upper end through the housing of the machine, between the cross-beams A², where it is supported in a suitable bearing, c', sustained from said cross-pieces. The said shaft C' is provided at one end or the other with a suitable pulley, C², for rotating the drum, said pulley, as indicated in the accompanying drawings, being located at the upper end of the shaft.

The drum C may be constructed in any suitable or desired manner, but, as herein shown, it is made hollow, and its walls cylindrical. Said walls may be made of wood or other material, and they may, as shown, be sustained concentrically with the shaft C' by means of 50 end pieces, c², held rigidly upon the shaft by means of flanged castings or hubs c², fixed to the shaft; or they may be supported in any other desired or preferred manner.

Upon the exterior surface of the drum C are placed spiral flanges D, which are preferably continuous, and may be constructed in any desired or preferred manner.

60 E E are outwardly-inclined beaters placed upon the drum C, in the spaces between the flanges D, said beaters preferably terminating in the same cylindric surface as the outer margins of the flanges D, and being back-

wardly inclined with reference to the direction of motion of the surface of the drum when the latter is rotated.

70 Exterior to the bolting-cloth B are located chambers F, inclosed in part by the stationary uprights A', and in part by the walls G, which may be constructed of wood, as herein shown, or of any other suitable material—as, for instance, of cloth or canvas—as described in an application for patent upon centrifugal separators filed by me September 12, 1883. The bottom head or lower horizontal end wall, G', of the outer housing or casing, which incloses 75 the chamber F, is, as herein shown, supported upon the cross-pieces a at the lower ends of the uprights A', and is provided with an outlet or spout, G², by which the bolted material, falling into the bottom of the chamber F, is 80 discharged from the machine. The chambers F are inclosed at their upper ends by a horizontal casing or head, G³, which also forms 85 the upper end of the chamber, laterally inclosed by the cylindric screen B. Said head G³ is, as herein shown, attached to the lower 90 surface of the cross piece A², but may be otherwise secured.

95 The walls G are, as here illustrated, composed of two inclined boards or panels, g, of wood, secured, preferably, by means of hinges g', Figs. 1 and 2, to the edges of the uprights A', and secured at their meeting edges by a strip, g², which is held at its upper and lower ends upon the stationary part of the housing 100 G. By this construction the housing may be readily opened, and access had to the screen B and drum C for the purpose of inspection or repair.

Beneath the lower end of the drum C is a 105 shallow cylindrical receptacle, H, having a bottom, h, and a rim, h', and provided with an inlet, H', through which the material to be separated is fed. Said receptacle H is herein shown, Fig. 3, as being secured in position by 110 being attached to the uprights A', and may be additionally upheld by braces h², Fig. 1. The rim h' of the said receptacle H is preferably circular and of the same diameter as the screen B, the lower circumferential rib, b', of 115 which is constructed to rest upon the upper edge of the said rim and to form a close joint therewith.

At the upper end of the machine is placed a stationary rim, I, corresponding to the rim 120 h' of the receptacle H, and secured in place by attachment to the uprights A⁴, said rim being also preferably secured at its upper edge to the head G³, which forms the top of the outer casing of the machine. The said 125 rim I fits at its lower edge upon the surface of the upper circumferential rib, b', of the screen-frame, so as to form a close joint therewith.

130 At the upper part of the chamber inclosed by the screen B, the receptacle H, and the rim I is located an outlet-opening, J, for the escape of the refuse or unbolted material, said opening J, as herein shown, Fig. 3, being

formed in one of the uprights A' above the upper end of the aperture A³ in said upright. In the operation of the machine constructed as so far described, it is obvious that the spiral ribs D and beaters E (if said beaters are present) will cause the air within the space between the drum and the screen to move around with the drum, so as to carry the material with it, and that said spiral flanges will produce a more rapid upward movement of the air and of the material in proportion as the rotary motion of the air-current is lessened. For the purpose of obstructing this rotary movement of the air by partially cutting off or reducing the area of the passage between the exterior of the drum and the surrounding screen, one or more vertical stops, partitions, or valves, K, are provided. Preferably, said valves are two in number and located at diametrically-opposite sides of the drum, as shown in Figs. 2 and 3. Said valves extend the greater part of the length of the cylinder, and are adjustably connected with the machine-frame, so that their inner faces may be adjusted to a greater or less distance from the surface of the drum.

As herein shown, the valves K are fitted to slide in the vertical slots A³ in the uprights A', and are made of considerable width, as best seen in Figs. 2 and 6. When thus broad, their faces adjacent to the drum are concaved to conform to the exterior curvature of the drum, as shown more clearly in Fig. 2. As a suitable and preferable means for adjustably securing the valves K in the slots A³ of the machine-frame, flanges K' are secured at either side of the strip forming the main part of each valve, at right angles thereto, so as to bear at their outer faces upon the sides of the slot A³, said flanges K' being provided with horizontal slots k, through which are inserted thumb-screws k', entering the walls of said slot A³, and reached from the outside of the machine. The inner faces of the valves K may be provided with a series of transverse corrugations or ribs, k², as illustrated at the left hand in Figs. 2 and 3, said ribs being horizontal or slightly inclined, as illustrated in detail, Figs. 6 and 7. The object of such ribs is to prevent the material thrown outwardly by the centrifugal action of the drum against the surface of the valves from falling vertically, the said ribs serving to support the material striking such valve-surface and retaining it until drawn away by the lateral movement of the air-current. By making the ribs k² inclined a slight upward movement of the material supported thereby is produced as it is carried laterally in the manner described, so that such material is continuously fed upward. In Fig. 8 the ribs k² are shown as being rounded in cross-sectional shape, so as to give a corrugated form to the surface of the valve, instead of being angular in shape, as shown in Fig. 7.

As a simple and economical means of constructing the flanges D, said flanges may be

made in the manner next described, and illustrated in Figs. 5, 9, and 10. As shown in said figures, said flanges consist of a series of 70 relatively short curved strips, D', of sheet metal, which are secured to the surface of the drum, and the meeting ends of which are lapped in such manner that the end of each strip, which is in advance in the rotary motion of the drum, is beneath the overlapping end of the strip adjacent to it. The strips are formed from curved sheet-metal blanks, one of which is shown in Fig. 10, said blanks being cut so as to form slits d, extending equal 80 distances inwardly from the concave edge thereof, as shown in said figure, and the parts d between the slits are bent alternately in opposite directions, as shown in Fig. 9, so as to rest flat upon the surface of the drum, to which 85 they may be secured in any convenient or desired manner. The cylindric portion of the drum, as herein shown, is made of wood, and the strips D' are conveniently secured thereto by screws or nails driven into the surface of 90 the drum through the apertures d² in the part d'.

As shown in Fig. 11, the flange D, at the lower end of the drum C, is transversely inclined or set at an angle to the face of the 95 drum, its outer edge being considerably higher than the edge which is secured to the drum, while, as the flange rises toward the top of the drum, the inclination is gradually diminished until, at the upper end of the drum, the 100 flange is nearly or quite horizontal. The effect of this construction is to give a more rapid upward impulse and movement to the material in the lower part of the bolt, and to more evenly distribute the work throughout the entire length of the bolt. Another effect of the greater inclination of the flange at the lower end of the drum is to lessen the force with 105 which the material is borne outward against the bolting-cloth, owing, manifestly, to the upwardly-inclined direction at which it leaves the surface of the flange. By this means the crowding of the lower end of the bolt is lessened, and, as before stated, the work is more evenly distributed throughout all parts of the 110 bolt. The upward movement of the material may further be facilitated or hastened by giving to the spiral flange D a wavy curvature, (indicated in Fig. 13,) and such undulatory curvature may be applied to the flange whether 115 the latter has the inclination last above referred to or not. In Fig. 13 the flange is shown as being inclined to the face of the drum, and the undulatory direction of the flange does not extend to its inner edge. When such undulations are given to the flange 120 D, and when the beaters E are also employed, said beaters are placed at the elevations of the flange, as shown, so as to impart the more violent centrifugal impulse to the material for 125 which said beaters are intended at the moment it has acquired the upward motion due to the rise in the flange.

Even with provisions, as above referred to,

for more evenly distributing the material and work throughout the length of the bolt, it is still common in centrifugal bolts for an excess of the material to obtain in the lower end of the bolt 5 and for the quantity to diminish toward the top. The outward impulse of the material is consequently greater in the lower and less in the upper parts of the bolt. As a compensation for this unequal outward pressure of the 10 material upon the bolting-cloth, I prefer to make the said cloth in sections of different fineness of mesh, the coarser being placed above the finer. In this construction the coarse particles and impurities of the material are retained 15 within the lower part of the bolt by the fineness of the screen-mesh, while in the higher regions of the bolt, where the outward pressure is diminished, they are equally retained by a cloth of coarser mesh. The fluffy and flaky 20 material, even if very fine, will not escape through the upper and coarser meshes, because of the air-current which tends to draw them upward. The screen-mesh at the upper end of the bolt may be quite coarse, and the capacity 25 of the machine thereby materially increased.

I claim as my invention—

1. The combination, in a vertical separator, of a rotating drum provided with a spiral 30 flange or flanges, a screen exterior to the drum, and one or more vertical partial partitions or valves arranged to constrict the space between the screen and the drum, substantially as and for the purpose set forth.
2. The combination, in a vertical separator, of a rotating flanged or winged drum, a screen exterior to the drum, and one or more adjustable partitions or valves arranged to constrict the space surrounding the drum, sub- 35 substantially as and for the purpose set forth.
3. The combination, in a vertical separator, of a rotating flanged or winged drum, a screen exterior to the drum, and an adjustable valve or partition, K, having a broad inner face ad- 40 jacent to the surface of the drum, substantially as and for the purpose set forth.
4. The combination in a vertical separator, of a rotating flanged or winged drum, and one or more adjustable vertical valves, K, 45 having the inner face transversely ribbed, substantially as described, and for the purpose set forth.
5. The combination, in a vertical separator,

of a rotating flanged or winged drum, a screen exterior to the drum, and a broad-faced vertical valve, K, concaved on its face to conform with the drum, substantially as and for the purpose set forth. 55

6. The combination, in a vertical separator, of a rotating flanged or winged drum, a screen exterior to the drum, one or more valves for constricting the space about the drum, and means for inwardly and outwardly adjusting said valve or valves from the exterior of the machine, substantially as described. 60

7. The combination, with the drum and exterior screen of a vertical bolt, of a spirally-arranged flange secured to the drum, said flange being inclined upwardly and outwardly from its inner to its outer edge, substantially 70 as and for the purpose set forth.

8. The combination, with the drum and exterior screen of a vertical bolt, of a spirally-arranged flange secured to the drum, said flange being inclined upwardly and outwardly 75 from its inner to its outer edge and having a greater inclination at the lower than the upper end of the drum, substantially as and for the purpose set forth.

9. The combination, with the drum and surrounding screen, of a vertical separator, a spirally-arranged flange or flanges of undulating curved form, substantially as shown, and for the purposes set forth. 80

10. In combination with the drum and surrounding screen of a vertical separator, a curved or undulating spirally-directed flange secured to the drum and beaters secured to the drum at the elevated points of the undulatory flange, substantially as described. 85

11. In a vertical separator constructed to carry the material being operated upon upward through the machine, the combination, with a flanged or winged drum, of a surrounding screen made in sections of unequal fine- 95 ness, the coarser sections being placed above the finer, substantially as and for the purpose set forth.

In testimony that I claim the foregoing as my invention I affix my signature in presence 100 of two witnesses.

LOUIS GATHMANN.
